UNITED STATES PATENT OFFICE

PAUL ADOLPHE CARTERET, OF NEUILLY SUR SEINE, FRANCE

SUSPENSION SPRING

Application filed April 22, 1930, Serial No. 446,830, and in France October 28, 1929.

The present invention relates to improvements in springs, particularly suspension springs for motor vehicles, whereby the oscillations of these springs are automatically damped.

The invention is essentially characterized by the combination of two superposed leaves one of which is connected at one end to the chassis, while the other leaf has its corresponding end movable and guided by means of double shackles or of slides, so that the movement of yielding and recovery of this spring produce friction between these leaves by means of which the oscillations of this spring are rapidly damped.

The invention comprises all the modes of construction in which the above combination is found, which combination may be either single or double or associated with other friction elements or with counter leaves serving to complete the spring.

The invention is clearly illustrated in the accompanying drawing, in which:—

Fig. 1 is a side elevational view of one form of the improved supporting spring.

Fig. 2 is a top plan detail of the spring leaves with the securing means removed.

Fig. 3 is a fragmentary elevational detail of the arrangement shown in Fig. 1 showing the action of one of the supporting shackles, and

Fig. 4 is a side elevational view partly in section of another form of supporting spring.

Similar characters of reference are employed in all of the above described views to indicate corresponding parts.

Referring now, more particularly to the drawing, there is provided two leaf springs *l* and *f* arranged in superposed relation with each other, the spring *l* having one end *a* pivoted to the forward end of the chassis while the opposite end *b* is free to move being pivoted to the outer end of a link *j* in turn pivoted to a bracket suspended from the chassis. The other leaf spring *f* has its opposite end pivoted to the pivot point of the link *j* as at *d* while the other end *c* is free to move relative to the leaf spring *l* being pivoted at the outer end of a link *j*

the inner end of which is pivoted at the fixed point of the support of the leaf spring *l*.

As the leaves *l* and *f* are pivoted in opposite directions to each other, when the spring yields they slide with respect to each other, on condition however that at least one of the leaves can slide with respect to the assembly bolt and in spite of the clamping action which the latter produces. In this connection it is to be noted that the ends 60 of the leaves are reversely curved at the points where they are mounted.

Care is therefore taken to form a slot *e* in one of these leaves, for example in the leaf *f* (Figure 2), in order to permit it to slide, in which slot is lodged a distance piece in the form of a plate *g* the thickness of which is a little greater than that of the leaf *f* which is traversed by the assembly bolt.

In Figure 2 will further be seen a certain number of lubricating holes distributed over the whole surface of the leaf for the purpose of lubrication.

Fig. 4 shows a constructional modification in which the free ends of the leaves, instead of being guided by shackles, bear against rollers *j*³, *j*⁴.

With the spring thus constructed, when it yields, the leaf *l* lengthens and produces an energetic friction upon the leaf *f* which lengthens in the reverse direction and is in rubbing contact over the whole of its surface.

If on the contrary the spring expands by curving more (particularly as the result of a sudden impact) the leaves move more and more in opposite directions and their mutual pressure increases with the increase in curvature of the leaves. Care is taken moreover to give the leaf *f* an initial curvature in the reverse direction to that of the other leaves, as is done for the same purpose with the counter leaves of the ordinary springs.

Moreover when the spring becomes in-curved, as stated above, the shackle *j* inclines towards the left and presses the leaf *l* more strongly upon the leaf *f*, which pressure is measured at each moment by the height *h*, 100

as is clearly shown in Figure 3, which shows in detail one of the ends of the spring.

The same is the case for the shackle j^2 .

The damping is thus constantly proportional to the amplitude of the oscillations.

The new spring thus forms a powerful brake, which promptly and effectively damps the oscillations. The braking action due to the friction is increased as explained above by the initial curvature of the leaves and by the play of the shackles.

It will be noted that the new springs comprise no weak point nor any break in continuity over the whole of their length.

15 They permit the shock absorbers to be dispensed with because they perform at the same time the function of springs and that of shock absorbers. Moreover, they prevent the movements of rolling and shimmy.

20 In fact, it will be noted that the entire spring is attached to the chassis by the fixed axes a and d of the two main leaves without any joint, thus eliminating the transverse reactions which produce rolling and shimmy, so

25 that the vehicle holds the road more satisfactorily; besides, the double main leaf reinforces the spring and constitutes a security element.

30 The springs maintain their ordinary appearance and the shock absorbers, their fittings, their assemblage, their adjustment and their inconveniences are eliminated.

The arrangements described above are naturally only given by way of example and 35 all the details of construction and embodiment may vary in all cases without on that account going outside the scope of the invention.

I claim:—

40 1. A suspension spring comprising two leaves each of which is secured at one end to a fixed point while the other end is free and positioned adjacent the fixed end of the other leaf, one of said leaves being provided 45 with a slot, and a stationary spacing plate mounted in the slot allowing relative longitudinal movement of the two leaves.

2. A spring comprising two leaves one of which has one end fixed while the opposite 50 end is mounted for movement while the other leaf has one end fixed near the movable end of the first leaf and its opposite end mounted for movement, said leaves being movable in directions opposite each other over their 55 entire length so as to be in friction with each other over their entire extent, and means for securing the free ends of these two leaves to the chassis in a manner that each of the two leaves is guided on the two free ends.

60 3. A spring comprising two main leaves having reversely curved ends movable relative to each other over the entire length, and in friction with each other over their entire extent, one leaf being solid and the other 65 being provided with a slot, a distance piece

mounted in the slot and secured relatively to said solid spring, and means securing the leaves to permit said relative movement.

4. A suspension spring comprising two superposed leaves each having one end secured to the chassis and its opposite end free, the fixed end of the spring being remote from each other, securing means for the middle portions of the leaves, one of the leaves being provided with a slot, and a spacing 70 plate mounted in the slot for allowing relative longitudinal movement of the two leaves and being fixed to the securing means.

5. A spring comprising two main leaves having reversely curved ends and movable 80 relative to each other and in frictional contact with each other their entire length, securing means associated with the middle portions of the leaves, one of the leaves being solid and the other being provided with 85 a slot, a distance piece mounted in the slot, and an adjustable bolt engaged through the slot for anchoring the distance piece to the securing means.

The foregoing specification of my "im- 90 provements in suspension springs" signed by me this 11 day of April, 1930.
